UNITED STATES PATENT OFFICE.

JOHN CARL AMIS, OF TOMS CREEK, VIRGINIA.

JIG.

1,146,682.

Specification of Letters Patent. Patented July 13, 1915.

Application filed June 23, 1914. Serial No. 846,761.

To all whom it may concern:

Be it known that I, JOHN C. AMIS, a citizen of the United States, and a resident of Toms Creek, in the county of Wise and State of Virginia, have invented certain new and useful Improvements in Jigs, of which the following is a specification.

This invention relates to jigs, adapted for use in the separation of base materials from mixtures as originally mined, such as slate from coal, and the main object thereof is to accomplish this result at any desired specific gravity, regardless of the per cent. of heavy or light materials, automatically.

15 A further object is to accomplish this result by passing the mixture over a suitable screen and subjecting the same to pulsations of water directed through said mixture.

20 A further object is to provide mechanical means for removing the heaviest materials from said mixture.

A further object is to provide a gage for regulating the depth of the bed of mixture 25 passing to said mechanical discharge means.

A further object is to provide an adjustable gate for gaging the specific gravity of the materials passing thereover.

A further object is to provide a dam for 30 permitting the lightest materials to pass from said jig directly.

A further object is to insure such separation at atmospheric pressure in one jig, and to provide means for accomplishing 35 such separation by a compressed air cushion in another jig, all automatically, and in a controllable manner.

My invention is fully described in the following specification, of which the accompanying drawings form a part, in which the same parts are designated by the same reference characters in each of the views, and in which:—

Figure 1 is a longitudinal, vertical, section 45 taken through a jig constructed in accordance with my present invention; Fig. 2 is a similar, but enlarged, view of a part thereof; Fig. 3 is a section taken on the line 3—3 of Fig. 2; Fig. 4 is a view similar to Fig. 2, 50 of a portion not shown in Fig. 1; and Fig. 5 is a plan view, fragmentarily, thereof.

In the drawings forming a part of this application I have shown a jig, comprising a screen α to which the unrefined coal is 55 passed from a hopper α^2 through the feed-box α^3 by means of a feeder α^4 , said coal

passing under a baffle-plate α^5 which tends to force the same toward the screen α , and said screen is vertically adjustable by means of bolts α^6 and nuts α^7 , as clearly shown in Fig. 1, said screen being hinged at α^8 to a fixed part of the screen support or frame of the jig.

The material on the screen is worked across the screen by pulsations of water from perforated pipes b arranged beneath the same, and the jets of water from which are evenly distributed over the under side of the screen by means of plates b^2 , said pipes b being provided with valves b^3 where-
by any sediment may be removed from the pipes and are also provided with gate valves b^4 and are connected with a rotary valve casing b^5 in turn connected with a feed pipe b^6 , and I provide a rotary valve b^7 within said casing having pockets b^8 in the periphery thereof, of any suitable number, size, or shape, and said casing may also be suitably formed to assist in delivering water to the pipes b , from the feed pipe, in pulsations, the number of which per minute, as well as the kind, are controlled by the pressure in the feed pipe, the angular velocity of the rotary valve b^7 , the shape and size of the pockets therein, and the adjustment of the gate valves b^4 , and a water-level x is maintained over the jig screen α . This water-level is maintained by means of a dam c , preferably adjustably held by means of bolts c^1 — c^1 , and which carries an adjustable, transversely arranged plate c^2 to regulate the depth of the bed of material passing thereunder, and above said dam c are a plurality of pipes or tubes c^3 which extend above the water-level and beneath which is a sloping plate c^4 which is integral with the dam c and adjustable therewith, said plate c^4 assisting in the formation of a passage c^5 divided, by means of a partition c^6 from another passage c^7 and both of which passages lead downwardly to a predetermined point.

At the mouth of the passage c^7 is a vertically adjustable gate d to gage the material going thereover, adjustable by means of a threaded bolt d^2 and hand-wheel d^3 , or suitable equivalent, and the partition c^6 is partly composed of a trap c^8 opening into the passage c^5 for a reason later explained.

Within the passage c^7 , adjacent the gate d , is a rotary discharge valve d^4 having suitably formed pockets therein to receive the

heaviest materials and convey them to the said passage, beneath said valve, and it will thus be seen that the mixture being acted upon is carried along the screen, because of its inclination, toward the plate e^2 and, in such movement, the heaviest materials settle to the bottom, the lighter thereover, and the very lightest rise to the top of the bed of mixture, all in stratified form, and the very lightest is carried over the dam e^5 by the flow of water thereover. If, however, the valve d^4 should engage more material than the capacity of any of its pockets, the trap e^6 is forced open and the excess material, large lumps, etc., drop into the passage c^3 , and all of the mixture lighter than that carried off by the valve d^4 and heavier than that at which the separation is to be made, passes under the adjustable plate e^2 to the gate d over which it is forced by the water pulsations and the forward movement of the mixture upon the screen, and this relatively heavy material falls into the passage c^3 . The tubes c^3 , being open at their tops, permit the water to pass thereinto in each pulsation, instead of said water being forced over the gate d and through the passage c^5 , and thus to the refuse elevator boot, not shown, but with which the lower ends of said passages c^3 and c^5 connect, and this open top arrangement of the tubes c^3 is of great importance in the proper operation of the jig, inasmuch as they thus serve as relief valves for the water pulsations therein. The lighter material, under a certain specific gravity, passes over the dam e^5 , thence over a de-watering screen e to permit superfluous water to escape, and thence to another unit having a screen c^2 hinged at e^3 and beneath which is arranged a perforated pipe b , similar in all respects to that already described, and the materials are carried along said screen c^2 toward an adjustable plate e^4 on a dam e^5 in the manner already set forth.

The dam e^5 has a sloping plate e^6 connected therewith and assisting, together with a partition f , to form a passage f^2 , a portion of said partition being hinged, as shown at f^6 , said partition also assisting in forming a passage f^4 and both of which passages lead to a refuse elevator not shown, and I also provide a gate e^7 , adjustable by means of slots therein and bolts e^8 , at the mouth of the passage f^2 , and it will be seen that the lightest materials pass over the dam e^5 , i.e. the water overflow, to another unit or compartment, if desired, for further refinement.

In the unit now being described I provide no tubes as at c^3 in the unit already described, the result being that air is confined in the pocket formed beneath the plate e^6 , this being an important part of the operation, and I also provide a needle-valve e^9 in the plate e^6 adapted to be actuated by a

float in such manner that the valve will open when water beneath the plate e^6 falls below a certain level to allow free passage of air, and closes when said water level is raised above said point, as it is of great importance that the amount of air in the chamber e^{11} , formed by the plate e^6 and dam e^5 , shall be constant, side webs e^{12} being provided on the said dam and plate to insure such chamber. Within the passage f^4 , adjacent its mouth, is a rotary discharge valve f^5 which is provided with pockets f^6 therein to carry off the heaviest materials from the screen e^2 and to the passage f^4 , and the hinged member f^3 opens when large lumps are engaged in the said discharge valve beyond the capacity of its pockets.

In operation, the material comes to the discharge end of this jig in a more or less stratified form, the heaviest at the bottom and the lightest at the top, and the former works under the plate e^4 on the dam e^5 and into the U-shaped tube or space between the said plate and the gate e^7 , entirely across the width of the jig, the heaviest particles being taken by the discharge valve f^5 and the lightest within said U-shaped tube passes over the gate e^7 . Assuming that we have a layer of slate or heavy material on the screen e^2 , a layer of coal or other light material on top of this and a column of slate or heavy material in the U-shaped tube and which balances, by weight, an equal area of the material on the screen; when the pulsation of the water begins, the water rushes up through the U-tube lifting the slate and carrying some of it over the gate e^7 , thus compressing the air in the chamber e^{11} to a degree and, when said pressure in the U-tube is sufficient, the water begins to flow through the material in the box and raises the same and allowing some of the material to take the place of that raised in the U-tube; as the depth of the slate in the jig box increases, the harder it is for the water to force its way through, and we have a more violent action in the tube, more compression in the air chamber and more slate carried off over the gate e^7 , and by this method we get a positive specific gravity separation indefinitely, for we do not have an accumulation of the very heaviest material on the screen. We also secure a uniform overflow entirely across the jig, and which is adjustable; a U-tube in ideal working condition because of the removal of the largest lumps by means of the discharge valve; we separate in fixed amounts and at uniform rates; we provide for the maintenance of a constant quantity of air in the chamber e^{11} ; and we may slope the screen in any desired degree.

It will thus be seen that I separate the heavier refuse materials from coal or other substances, by means of water pulsations, under absolute control, mechanical discharge

valves, and water compressed air, and any number of units may be employed, and other changes made over the form described, within the scope of the following claims, and, with such reservation,

What I claim as new, and desire to secure by Letters Patent, is:

1. A jig, comprising a support, a screen thereon, a feed for directing a mixture onto said screen, an adjustable dam over which the lightest materials of said mixture may pass, means for supplying water, in pulsations, to said jig, through the mixture on said screen, mechanical means for removing the heaviest materials of said mixture from said screen, a sloping plate forming an air chamber thereover, an automatic air-valve for said chamber, and an adjustable gate beneath said chamber for controlling the specific gravity of materials passing thereover, the air in said chamber being compressed by the water pulsations to force accumulating

materials in the U-tube so formed over said gate, as forced upwardly by said pulsations.

2. A jig, comprising a support, a screen thereon, a feed for directing a mixture onto said screen, means for separating the lighter materials of said mixture from the heavier, mechanical means for removing the heaviest materials from said screen, a hinged trap arranged over said mechanical means to accommodate unusually large lumps of material and permit the same to escape from said mechanical means, and adjustable means for regulating the depth of the mixture passing to said mechanical means.

In testimony whereof I have signed my name to this specification in the presence of the subscribing witnesses.

JOHN CARL AMIS.
